CLAIM

The ornamental design for a display screen with an animated graphical user interface, as shown and described.

DESCRIPTION

FIG. 1 is a front view of a first image in a sequence for a display screen with an animated graphical user interface; FIG. 2 is a second image thereof; FIG. 3 is a third image thereof; FIG. 4 is a fourth image thereof; FIG. 5 is a fifth image thereof; FIG. 6 is a sixth image thereof; FIG. 7 is a seventh image thereof; FIG. 8 is an eighth image thereof; and, FIG. 9 is a ninth image thereof.

The broken line showing of the device illustrates environmental structure. All other broken lines showing the display screen and portions of the graphical user interface illustrates portions of the article. None of the subject matter depicted in the aforementioned broken lines forms part of the claimed design.

The appearance of the transitional image transitions sequentially between FIGS. 1-9. The process or period in which one image transitions to another image forms no part of the claimed design.
